UNITED STATES PATENT OFFICE

2,025,628

GASOLINE DISPENSING DEVICE

William A. Williams, Rome City, Ind.

Application February 6, 1935, Serial No. 5,281

1 Claim. (Cl. 221—100)

My invention relates to improvements in devices for dispensing gasoline at filling stations, or in other places where gasoline is sold or delivered to customers, and it consists in the combinations, constructions and arrangements herein described and claimed.

An object of my invention is to provide a device in which the use of complicated pumping mechanism which is costly to make and to maintain, is obviated.

A further object is to provide a device which is positive in action, having no moving parts except valves to open and close pipe lines, and which therefore does not subject users to loss through frequent failure to function satisfactorily, as do the more complicated devices.

A further object is to provide a simple construction which is economical in operation, since there is nothing to wear out or get out of order.

A further object is to provide a safeguard against theft by the assembly of all connections inside of the locked machine.

Other objects and advantages will appear in the following specification, and the novel features of the invention will be particularly pointed out in the appended claim.

My invention is illustrated in the accompanying drawing forming part of this application, in which:

Figure 1 is a side elevation of a dispensing device forming one embodiment of the invention, and,

Figure 2 is a vertical sectional view.

In carrying out my invention I provide a casing or housing 1 which may be made of any suitable material, but which is preferably made of metal. It is provided with openings, such as those shown at 2, 3 and 4 for access to the interior mechanism, these openings being preferably closed by hinged doors, such as those shown at 5, 6, 7 and 8' respectively. Suitable locking means, not shown, may be used in connection with these doors so as to prevent any tampering therewith.

Supported upon the top 1a of the casing or housing 1, is a tank 8 which is preferably made of glass. This tank has at its top a relief valve 9 whose function will be explained later.

At 10 I have shown a portion of a storage tank for the fuel, such as gasoline, which is to be dispensed. A filling tube 11 extends upwardly from the tank above the ground line 12, and terminates just inside the door 5 so that when the latter is opened connection can be made to the end of the pipe 11 for filling the tank 10.

A pipe 13 is provided, this pipe extending from

the tank 10 above the ground line. It is provided with a valve 14 and with an adjustable pressure regulator shown diagrammatically at 15. The pipe 13 is designed to be connected with a source of compressed air, not shown, so as to put the fuel in the tank 10 under pressure.

Extending from a point near the bottom of the storage tank 10 and communicating with the tank 8 is a pipe 16 which is provided with a valve 17. A pipe 18 extends from a sump 19 in the bottom 10 of the tank, and is provided with a valve 20. An overflow pipe 21 is disposed centrally of the tank 8 and is provided with an adjustable extension 22, by means of which the effective length of the pipe 21 may be changed so as to register with gauge 15 marks 23. These gauge marks, as will be observed from Fig. 1, have numbers to indicate the amount dispensed, this amount being preferably measured in gallons.

The lower end of the pipe 21, which is an overflow pipe, communicates with a transfer tank 24, a valve 25 being provided as shown in the drawing.

A short drain pipe 26 having a valve 27 extends from the bottom of the tank 8 and communicates 25 with the interior of the transfer tank 24. At the bottom of the transfer tank is a short pipe 28 having a valve 29, the lower end of this pipe communicating with the pipe 16, as shown. A pipe 30 communicates at its lower end with the tank 10, and at its upper end with the upper end of the tank 24. This pipe has a valve 31.

A dispensing hose 32 is provided having the usual nozzle and retaining means 33 therefor. This hose communicates with a discharge pipe 35 30, which is controlled by a valve 34.

From the foregoing description of the various parts of the device the operation thereof may be readily understood. Normally all of the valves are closed. The tank 10 is filled, as stated, 40 through the medium of the pipe 11.

The valve 14 is opened to permit compressed air to enter the interior of the tank 10 until a desired pressure is attained, this pressure being indicated by the pressure valve 15.

The valve 14 is then closed and the tank 10 is under pressure. The tank 8 may be filled by opening the valve 17. This will permit the liquid to flow through the pipe 16, under pressure until it has reached the top of the overflow pipe 50 21, when it will pass downwardly into the transfer tank 24, the valve 25 having been opened to permit the passage of the fluid into the transfer tank. When the liquid is to be dispensed the end of the hose is put into the tank of an auto- 55

mobile or container and the valve 35 is turned to draw off the desired quantity of the fluid as shown by the gauge marks 23. When the desired quantity has been drained the valve 35 is then closed. 5 This process may be repeated as long as there is fluid in the tank 10 and pressure thereon.

If it is desired to drain the bowl 8 the valve 26 is opened and the contents of the bowl may be drained into the transfer tank 24.

10 The accumulation from the overflow may be returned to the tank 10 against the pressure therein in the following manner. The valves 17, 21 and 25 are closed and the valves 31 and 29 are opened. Since both pipes 16 and 30 are under 15 the same pressure, i. e. the pressure in the tank 10, the pressure on the transfer tank 16 will be equalized and the fluid, such as gasoline, will flow by gravity through the pipe 28 and the pipe 16 downwardly into the tank 10. The valves 29 and 20 31 are thereupon closed and when it is desired to again fill the bowl or tank 8 the valves 17 25 may be opened. When it is desired to clean out the tank of any sediment or of any water that may have accumulated in the tank, 25 the valve 17 is closed at the top of the pipe 16, and the valves 29 and 31 being closed the valve 20 may be opened and the pressure on the inside of the tank 10 will then force anything which has 30 accumulated in the sump 19 through the discharge pipe 18, after which the valve 20 may be closed.

It will thus be seen that I have provided an efficient dispensing device in which accurate

amounts of liquid, such as gasoline, can be elevated, measured and dispensed without the necessity of pumping devices, which as stated, are apt to get out of order and to deliver other quantities of fluid than they are rated to deliver, because of leakage, etc. It will be observed that the closures are so disposed as to permit easy access to the various valves for manipulating the device in elevating the liquid into the bowl, in draining it from the bowl, in dispensing it, and in controlling the overflow as well as in cleaning the tank 10 of accumulations therein and in returning the liquid to the tank 10 without the necessity of relieving the pressure in the latter. 5 10 15

I claim:—

A dispensing device for liquids, comprising a storage tank for the liquid, means for introducing air under pressure into the tank, an elevated dispensing tank, controllable connections between said tanks for conveying liquid from the storage tank to the elevated tank, means for discharging the dispensing tank at will, a transfer tank disposed below the dispensing tank and above the storage tank, means for draining the contents of the dispensing tank into the transfer tank, means for returning the contents of the transfer tank to the storage tank against the air pressure in the latter, said last means comprising a controllable pipe extending from the storage tank to the top of the transfer tank, and a controllable pipe leading from the bottom of the transfer tank and communicating with the storage tank. 20 25 30
